UNITED STATES PATENT OFFICE.

MATTHEW E. WESALA, OF CHICAGO, ILLINOIS.

LEGGING.

Application filed July 15, 1925. Serial No. 43,870.

This invention relates to leggings especially adapted for industrial use and has for an important object the provision of simple and reliable means to protect the fore part 5 of the legs from damage by acids, molten metal, and the like.

More specifically, the invention has for an object the provision of a legging impervious to acids, burns and like destructive influences in which the seam or seams thereof and the clip fastening rivets are effectively protected from destructive contact with dropping acids employed industrially or otherwise.

A further and equally important object is to provide a legging in which the two attaching clips are swivelled to the sides of the legging and in which the usual longitudinally extending metal strip is dispensed with so that the legging may be compactly folded for shipping and handling in trade.

A further and equally important object is to provide a legging which is of highly simplified construction, durable in use, and cheap to manufacture.

Other objects and advantages will be apparent during the course of the following description.

In the accompanying drawing forming a part of this application and in which like numerals are employed to designate like parts throughout the same.

Figure 1 is a perspective of the improved legging, a protecting strip of the same being partly detached to illustrate a seam at the front of the legging;

Fig. 2 is a vertical sectional view through the legging applied;

Fig. 3 is a horizontal sectional view taken on line 3—3 of Fig. 2.

In the drawing, wherein for the purpose of illustration is shown a preferred embodiment of the invention, the numeral 5 generally designates the body of the improved legging, which body consists of a pair of similarly formed or cut sections having their forward edges overlapped and joined by stitching 6, or by other suitable means. Fig. 1 clearly illustrates that a strip 7 of protective material is extended over the meeting portions of the sections of the body 5 and is secured thereto by a suitable cement. It will be seen that when the protecting strip 7 is cemented over the seam at the forward portion of the legging, acid and the like will be prevented from lodging in the seam.

Also, the overlapping forward edges of the sections of the body 5 and the strip 7 provide a triple thickness at the front of the legging whereby the legging will remain in place on the leg and will not collapse. However, the triple thickness at the front of the legging will not be sufficient to prevent the leggings from being collapsed for shipping purposes.

A pair of U-shaped clips 10 are pivoted at opposite sides thereof to the body 5 as indicated at 11 and may assume the full line position illustrated in Fig. 1 or the dotted line position illustrated in Fig. 2. The clips 10 may be easily attached to the leg and will hold the legging firmly in place. Fig. 3 illustrates that the back of the legging is open for the free circulation of air to keep the fore part of the leg cool and to allow the legging to be easily and quickly applied or removed.

In carrying out the invention, the lower portion of the legging is flared to extend completely over the shoe and thereby protect the same. This flaring of the body may be brought about by increasing the width of the sections of the body 5 at the lower end thereof.

In summarizing it will be seen that a legging constructed in accordance with this invention is characterized by simplicity, light weight, and simple means to provide for the free circulation of air.

The unusual acid resisting qualities, the simple attaching means, the light weight, the trouser and shoe protecting means, and the simple means for compactly folding the legging, all make the invention extremely useful and desirable.

Figure 1 illustrates that the heads of the swivel members 11 are covered by small strips 18 of acid resisting material.

Having thus described the invention, what is claimed is:

1. A legging comprising a body consisting of a pair of similarly formed sections having their forward edge portions overlapped and firmly fastened together, a strip of material cemented to the forward portions of said sections, and spring clips swivelled at the sides of said body and forming an attaching means for the legging, said strip and the adjacent portions of the sections of said body forming a means to hold the legging against easy bending when applied.

2. A legging comprising a body consisting of a pair of sections having their forward portions overlapped and firmly connected, a strip of acid resisting material secured 5 to the forward edge portions of said sections, and spring clips swivelled to said body and forming an attaching means for the legging, said strip and the adjacent portions of said sections of said body forming a means to hold the legging against easy bending when applied, the rear edges of said body being spaced from each other to allow the circulation of air.

3. A legging comprising a body consisting of a pair of similarly formed sections 15 having their forward edge portions over-

lapped and firmly fastened together, a strip of material cemented to the forward portions of said sections, spring clips swivelled at the sides of said body and forming an attaching means for the legging, said strip and the adjacent portions of the sections of said body forming a means to hold the legging against easy bending when applied, the rear edges of said body being spaced from each other to allow of the free circulation of air, and protective members extending over the swivel connections for said clips.
